SHADE PULL

Joseph O'Malley, New Bedford, Mass.

Application May 23, 1938, Serial No. 209,573

1 Claim. (CL. 156—40)

The present invention relates to shade pulls for window shades and has for its object to provide an attachment of this character embodying means for engaging the shade stick without injuring the portion of the shade to which the pull is attached, and which at the same time presents a neat and ornamental appearance, relatively inexpensive to manufacture and is otherwise well adapted to the purposes for which the same is intended.

Other objects and advantages reside in the details of construction as more fully hereinafter described and claimed, reference being had to the accompanying drawing forming part hereof, wherein like numerals refer to like parts throughout, and in which—

Figure 1 is a front view of the lower end of a window shade showing the pull secured in position thereon.

Figure 2 is a sectional view taken substantially on a line 2—2 of Figure 1 but with the cord, hereinafter described, omitted.

Figure 3 is a side view of the pull, and

Figure 4 is a front view of the pull partly broken away to show one of the internal lugs hereinafter described.

Referring now to the drawing in detail, the numeral 5 designates a window shade having the usual shade stick 6 secured along its bottom edge, the stick being held against movement within the hem or pocket 7 by means of the usual rivet 8, said rivet being of tubular formation as shown in Figure 2 of the drawing.

The shade pull designated generally at 9 is formed as a crotch or yoke comprising a pair of substantially flat tines or plates 10 of any suitable material possessing sufficient resiliency to enable the plates to be sprung apart in order that lugs 11 formed on the inner surfaces of the tines or plates may be inserted into position in the opposite ends of tubular rivet 8, the plates being connected to each other at their lower ends by a

web or intermediate portion 12, and from the latter depends a tubular finger gripping stem or handle 13. The free ends of the plates converge toward each other, as clearly shown in Figures 2 and 3 of the drawing, to conformably rest against the opposite surfaces of the triangular shaped shade stick 6. The stem or handle 13 is provided with a bore 14 within which the cord 15 of a shade tassel 16 may be inserted for securing the cord to the stem. The cord 15 extends upwardly through bore 14 and is secured in position by means of a knot (not shown) formed at its upper end, or in any other suitable manner.

It will be apparent from the foregoing that the shade pull attachment constructed in accordance with the invention is especially constructed for application to a known form of existing shade without modification or alteration of the latter and that it will present a neat and attractive appearance and provide a shade pull attachment which will prevent injury to the shade during long periods of use.

It is believed the details of construction and manner of use of the device will be readily understood from the foregoing without further detailed explanation.

Having thus described the invention, what I claim is:

A shade pull attachment for an existing window shade having a transversely disposed stick secured within a pocket at the lower end thereof by means of a tubular rivet that is open at its opposite ends, said attachment consisting of a resilient yoke having oppositely disposed flatlike tines having upon their inner faces integral lugs, said tines being adapted to be forcibly sprung for positioning against the opposite sides of said pocket with their lugs occupying the opposite ends of said tubular rivet thereby to positively lock said yoke in position, and a pull-cord connected with the intermediate portion of said yoke.

JOSEPH O'MALLEY.
